YIELDABLE CLUTCHING MEANS

Jacob Wohlfeld, Detroit, Mich., assignor to
George Lovequest, Detroit, Mich.

Application May 23, 1934, Serial No. 727,136

20 Claims. (Cl. 123—90)

The invention relates to yieldable clutching means for valve operating mechanism and other motion transmitting systems.

An object of the invention is to provide yieldable clutching means of durable, compact, and inexpensive construction suitable for use in various motion transmitting systems, as in the valve operating mechanism of an internal combustion engine to minimize noise and play and to automatically compensate for variations in the length of the valve caused by temperature changes and wear, the clutching means being capable of mounting in a self-contained tappet permitting replacement of a tappet of conventional type.

Another object of the invention is to provide a yieldable clutching device having spring-urged friction means through which the operating pressure is transmitted, and a more specific object is to form the friction means by a confined plug of plastic or deformable material.

The invention further consists in the several features hereinafter described and claimed.

In the accompanying drawing,

Fig. 1 is a sectional elevation of a valve operating mechanism equipped with a slack adjuster having yieldable clutching means embodying the invention, and

Fig. 2 is a detail view of some of the slack adjuster parts.

In the drawing, 10 designates the cylinder block of an internal combustion engine provided with the usual poppet valve 11 engageable with a valve seat 12 and having its stem 13 slidably mounted in the block and urged to valve-closing position by the usual surrounding valve spring 14 bearing on a valve washer, 15 held on the stem by a retainer 16. A tappet member 17 is slidably mounted in the cylinder block below and in axial alignment with the valve stem and has the usual enlarged lower end 18 periodically lifted by a cam 19 on a cam shaft 20 to thereby actuate the valve.

It will be obvious that for the type of valve operated through a rocker arm, the valve stem 13 is replaced by the usual valve rod or push rod which may also be regarded as a valve stem.

The tappet member 17, instead of having the usual adjusting screw means, is provided with the yieldable clutching means of the invention.

The tappet member forms a cylinder into the upper end of which is forced a tubular plunger body 21 having an annular flange 22 at its upper end engaging the upper face of the tappet member. A coiled spring 23 is housed within the tappet member below the plunger body and bears at

its upper end on a disk-like spring seat member 24 limited in its upward movement by the lower end of the plunger body. A relief opening 25 is drilled into the lower portion of the tappet member.

The plunger body 21 has formed therein aligned upper and lower bores 26 and 27, respectively, communicating with an intermediate upwardly diverging conical bore 28, the upper bore 26 being of larger diameter than the lower bore 27. An upper plunger 29 is slidably mounted in the bore 26 and projects upward from the plunger body to engage the lower end of the valve stem 13. A lower plunger 30 is slidably mounted in the bore 27 and has a projecting conical lower end engageable with the upper face of the spring seat member 24, a recess 31 being formed in this face to receive the conical end. Between the plungers 29 and 30 is interposed a compact, substantially voidless plug or briquet 32 of soft, plastic or deformable coherent material, such as graphite, although in some instances lead, a plastic amalgam, or rubber can be used. Fine powders, such as of carbon or metals, for instance, aluminum, are also usable. If desired, graphite may be mixed with the powders. The plug of solid but flowable material is confined by the plungers in the conical bore 28 which it frictionally engages, and under pressure fills the entire space between the adjacent end faces of the plungers, the flowable material and the plug or mass formed thereby being substantially incompressible. The space within the conical bore forms what may be termed an extrusion chamber for the deformable plug. While the bores 26 and 27 and the plungers therein are here shown to be of circular cross-section, it will be obvious that other cross-sections may be used.

Before the tappet assembly is installed in the engine, the free overall length of the assembly is slightly greater, say 0.015 inch, than the normal distance between the cam and lower end of the valve stem, and the spring 23 forces the spring seat member 24 into abutment with the lower end of the plunger body 21. When the tappet assembly is installed, the plunger 29 engaging the lower end of the valve stem gradually moves downward under urge of the valve spring 14 until the valve engages its seat and a small clearance, say 0.030 inch, exists between the spring seat member 24 and the bottom face of the plunger member, it being noted that the smaller plunger 30 moves farther than the larger plunger 29. During this movement of the plungers, the interposed plug 32 lengthens and changes its shape, 55

but the volume of the plug remains substantially unchanged. The deformable material presents a smooth surface which is in substantially continuous or unbroken slidable contact with the walls 5 of the chamber..

In operation, the valve is periodically actuated by the rotating cam shaft, the tappet member forming a motion-transmitting compression member. In the interval during which the valve 10 is closed, the pressure of the tappet spring 23 acting upward through the valve seat member 24, the lower plunger 30, the plastic or flowable material 32, and the upper plunger 29, tends to increase the length of the tappet. This pressure is 15 opposed by the somewhat greater valve spring pressure with the result that the tappet completely fills the space between the cam and the lower end of the valve stem, but does not lift the valve off its seat.

20 When the cam 19 lifts the tappet member 17, the upper plunger 29 lifts the valve from its seat. During this movement, the force acting downward through the valve stem 13 is transmitted through the upper plunger 29 which in turn 25 transmits it to the plastic or flowable material forming the plug 32. Some of this force is used in overcoming the friction caused by moving the plastic material downward in the conical bore 28 of the plunger body 21 and in changing the shape 30 of the plug, the balance of the force being transmitted to the smaller lower plunger 30 which in turn transmits it to the spring seat member 24, then to the spring 23 and to the bottom portion 35 of the tappet member 17. During the interval from valve opening to maximum valve velocity upward, the valve spring pressure plus the force due to the inertia of the valve, valve spring, washer, retainer and upper plunger tend to shorten the tappet, while the tappet spring and 40 friction of the flowable material oppose this total force. During the interval from maximum valve velocity upward to maximum valve velocity downward, the valve spring pressure minus the force due to the inertia of the valve, valve spring, washer, retainer and upper plunger and plus the force due to the inertia of the tappet assembly (less upper plunger) tend to shorten the tappet, and the tappet spring and friction of the flowable material oppose this total force. During 45 the interval from maximum valve velocity downward to valve closing, the forces acting are the same as those in the interval from valve opening to maximum valve velocity upward. The forces due to the inertia of the tappet spring seat member 24, lower plunger 30 and flowable material, 50 although small, are added to the tappet spring pressure for the interval from maximum valve velocity upward to maximum valve velocity downward, and are subtracted from tappet spring pressure for the interval from valve opening to maximum valve velocity upward, and for the interval from maximum valve velocity downward to valve closing. By varying the tappet spring pressure, the relative areas of the upper and 55 lower plungers, the friction or flowability of the plastic material, and the shape of the space through which the plastic material moves, to suit any particular valve mechanism, it is possible to maintain a tappet assembly length that 60 will fill the space between the cam and the lower end of the valve stem, with a positive seating of the valve and full valve lift, except for a very slight shortening during the valve-open period, say considerably less than 0.001 inch.

70 75 If the valve stem lengthens incident to an in-

crease in temperature and the valve tends to ride, the upper plunger 29 gradually moves downward until the valve fully seats and a clearance of, say, 0.038 inch exists between the spring seat member 24 and the lower end of the plunger 5 body 21.

The pressure or force acting on the upper plunger 29 is transmitted to the lower plunger 30 through the plastic or flowable material which functions like a plastic metal, has a comparatively slow action, and can be confined under the operating pressures without appreciable loss. The plastic or flowable material thus exerts a damping effect. When the plunger 29 moves downward, the flowable material is extruded 10 from the larger plunger bore 26 to the small plunger bore 27, and the smaller plunger 30 moves downward a greater distance than the upper plunger. When the lower plunger moves upward, the flowable material is lifted relatively 15 freely as a briquet away from the tapered walls of its chamber, and the upper plunger moves with the flowable material until the upper plunger abuts against the valve stem and stops. The lower plunger continues to move until the flowable material changing form entirely fills the confining space. Obviously, the force applied to the smaller plunger necessary to move the larger plunger is less than that applied to the larger plunger in order to move the smaller plunger, 20 considering the plunger body assembly as a unit consisting of the parts 21, 29, 30, and 32.

In general, the tappet assembly herein described will automatically, when in action, increase or decrease in overall length to suit the 35 variations in distance between the cam and the end of the valve stem, so that the valve will seat positively and at the same time will have zero tappet clearance.

A satisfactory plug or briquet can be prepared 40 by mixing fine graphite with light oil or kerosene, all or most of the liquid being squeezed out under operating pressures. While the briquet can be removed from the plunger body intact after a considerable period of pressure, it will 45 readily crush between the fingers, indicating that there is no tendency for it to become rigid or non-flowable. The lubricating quality of graphite also makes it a desirable material.

While the yieldable clutching means of the invention is here shown to be embodied in a slack adjuster for a valve-operating mechanism, it is also applicable to other motion-transmitting systems wherein it is desired to minimize lost motion, to compensate for variations incident to 55 temperature changes and other causes, and to permit motion in one direction more freely than in the opposite direction. Among such systems are brake systems, shock absorbers, door checks, remote control mechanisms, jacks, tool fixture 60 locks, and the like.

What I claim as new and desire to secure by Letters Patent is:

1. The combination of a body having bores and a chamber between and communicating with said bores, plungers in said bores, a compact, substantially voidless mass of soft, solid but flowable material confined in said chamber by said plungers and frictionally engaging the walls of said chamber, and yielding means for applying 65 pressure to said material through one of said plungers.

2. The combination of a body having a pair of bores of different diameter and a conical chamber between and communicating with said bores. 70

75

plungers in said bores, a mass of flowable material of high internal friction confined in said chamber by said plungers and engaging the walls of said chamber, and yielding means for applying pressure to said material through the smaller plunger.

3. The combination of a motion-transmitting member having a pair of bores extending in the direction of motion, there being a chamber between and communicating with said bores, plungers in said bores, a compact, substantially voidless mass of soft, solid but flowable material in said chamber frictionally engaging the walls of said chamber, and spring means in said member for applying pressure to said material through one of said plungers.

4. The combination of a tubular member having a pair of axially spaced bores adjacent one end extending longitudinally of said member, the outer bore being of larger diameter than the inner bore and there being a communicating chamber between said bores, plungers slideable in said bores, a compact, substantially voidless mass of soft, solid but flowable material confined in said chamber by said plungers and frictionally engaging the walls of said chamber, and spring means in said tubular member for applying pressure to said material through the smaller plunger.

5. The combination of a tubular member having a pair of axially spaced bores adjacent one end extending longitudinally of said member, the outer bore being of larger diameter than the inner bore and there being a communicating chamber between said bores, plungers slideable in said bores, a mass of solid but flowable material confined in said chamber by said plungers and frictionally engaging the walls of said chamber, spring means in said tubular member for applying pressure to said material through the smaller plunger, and stop means for limiting the movement of said spring means.

6. A slack adjusting tappet comprising a movable tubular member, a plunger body secured in one end of said member and having bores at opposite ends extending longitudinally of said member, there being a chamber between and communicating with said bores, plungers slideable in said bores, a mass of solid but flowable material confined in said chamber by said plungers and frictionally engaging the walls of said chamber, and spring means in said tubular member for applying pressure to said material through the plunger at the inner end of said plunger body.

7. Yieldable clutching means comprising a pair of relatively movable members, friction means for resisting relative movement of said members including a compressed but flowable mass of graphite, and yielding means for applying pressure to said friction means and tending to move one member with respect to the other.

8. Yieldable clutching means comprising a pair of relatively movable members, friction means for resisting relative movement of said members including a compressed but flowable mass of powdered material, and yielding means for applying pressure to said friction means and tending to move one member with respect to the other.

9. Yieldable clutching means comprising a pair of relatively movable members, friction means for resisting relative movement of said members including a compressed but flowable mass of powdered metal, and yielding means for applying pressure to said friction means and tending to move one member with respect to the other.

10. Yieldable clutching means comprising a

pair of relatively movable members, friction means for resisting relative movement of said members including a compressed but flowable mass of plastic metal, and yielding means for applying pressure to said friction means and tending to move one member with respect to the other.

11. Yieldable clutching means comprising a pair of relatively movable members, friction means for resisting relative movement of said members including a compressed but flowable mass of powdered carbon, and yielding means for applying pressure to said friction means and tending to move one member with respect to the other.

12. Yieldable clutching means comprising a pair of relatively movable members, friction means for resisting relative movement of said members including a compressed but flowable mass of graphite bearing material, and yielding means for applying pressure to said friction means and tending to move one member with respect to the other.

13. The combination of a body having a chamber with walls, members movable in said body and communicating with said chamber, and a compact, substantially voidless mass of soft, solid but flowable friction material in said chamber for transmitting pressure between said members and deformable by movement along said walls to retard relative movement.

14. The combination of a body having a chamber with converging walls, plungers movable in said body and communicating with said chamber, and a mass of solid but flowable material in said chamber for transmitting pressure between said plungers and deformable by movement along said converging walls to retard relative movement.

15. The combination of a body having a chamber with converging walls, a member relatively movable in said body and communicating with said chamber, and a mass of solid but flowable friction material in said chamber engageable with said member and deformable by movement along said converging walls to retard relative movement of said body and member.

16. The combination of a pair of relatively movable members, and friction clutching means for resisting relative movement of said members and comprising a compact, substantially voidless mass of soft, solid but flowable friction material, said material being substantially incompressible and having a smooth deformable surface in substantially continuous frictional contact with the surfaces of said members.

17. The combination of a body having a pair of guide openings of different cross-sectional area and a chamber at the inner ends of said openings, members slidably fitting in said guide openings and forming the opposite ends of said chamber, and a dense mass of soft, solid but flowable material confined in said chamber by said members and having a clutching engagement with the walls of said chamber, said chamber being larger at the end defined by the larger guide opening to permit relatively easier movement of said material toward said end than toward the smaller end, and means acting through the smaller member to apply pressure to said material in a direction tending to effect the free movement of said material.

18. Yieldable clutching means comprising a pair of relatively movable members, friction means for resisting relative movement of said

members including a compressed but flowable mass of dense, solid plastic material, and yielding means for applying pressure to said friction means and tending to move one member with respect to the other.

19. The combination of a pair of relatively movable members, and friction means for resisting relative movement of said members comprising a confined mass of compact, soft, solid but

10 flowable graphite.

20. The combination of relatively movable interfitting members forming a chamber, and friction clutching means for resisting relative movement of said members comprising a dense, substantially incompressible, briquet-like mass of soft, solid but flowable coherent material confined in and filling said chamber and having a friction clutching engagement with walls of said chamber.

JACOB WOHLFELD. 10
